US00D608094S

(12) **United States Design Patent**
Concari et al.

(10) **Patent No.:** US D608,094 S
(45) **Date of Patent:** ** Jan. 19, 2010

(54) **CASE FOR SOCKET WRENCH
ACCESSORIES**

(75) Inventors: **Gabriel E. Concari**, Eldersburg, MD (US); **Darren B. Moss**, York, PA (US)

(73) Assignee: **Black & Decker Inc.**, Newark, DE (US)

(**) Term: **14 Years**

(21) Appl. No.: **29/329,295**

(22) Filed: **Dec. 11, 2008**

(51) **LOC (9) Cl.** 03-01

(52) **U.S. Cl.** D3/282; D3/294; D3/905

(58) **Field of Classification Search** D3/201, D3/203.1, 260, 262, 273-274, 276, 282, 294-295, D3/315, 903, 905; 206/349, 372-378

See application file for complete search history.
